GRINDING TOOL GUIDE

Thomas L. Taylor, Detroit, Mich.

Application December 29, 1943, Serial No. 516,079

3 Claims. (Cl. 51—241)

1

The present invention relates generally to the art of grinding the edge of plate steel through the medium of a pneumatically driven, hand-manipulated grinding tool, and has for its primary object to provide, in a manner as herein-after set forth, a guide for said tool comprising a novel construction and arrangement whereby the edge of the work may be expeditiously and uniformly ground.

Another very important object of the invention is to provide a guide of the aforementioned character which will permit the edge of the work to be ground at any desired angle.

Still another important object of the invention is to provide a guide of the character described which is adapted to be readily adjusted to accommodate plate of substantially any size and thickness.

Other objects of the invention are to provide a grinding tool guide which will be comparatively simple in construction, strong, durable, highly efficient and reliable in use, compact and which may be manufactured at low cost.

All of the foregoing, and still further objects and advantages of the invention will become apparent from a study of the following specification, taken in connection with the accompanying drawings wherein like characters of reference designate corresponding parts throughout the several views, and wherein:

Figure 1 is a view in side elevation of the portion of the device which carries the pneumatic grinding tool, certain portions thereof being removed.

Figure 2 is a view in front elevation thereof, certain parts being omitted.

Figure 3 is a top plan view.

Figure 4 is a view in front elevation of the usual guard of a grinding tool.

Figure 5 is a detail view in cross section, taken substantially on the line 5—5 of Figure 1.

Figure 6 is a view in side elevation thereof.

Figure 7 is a view in horizontal section, taken substantially on the line 7—7 of Figure 2.

Figure 8 is a detail view in vertical section, taken substantially on the line 8—8 of Figure 1.

Figure 9 is a perspective view of one of the brackets.

Figure 10 is a detail view in vertical section, taken substantially on the line 10—10 of Figure 6.

Referring now to the drawings in detail, and to Figures 6, 7 and 10 thereof in particular, it will be seen that reference character 1 designates a pair of angular metallic arms. On one end,

2

the arms 1 are provided with clamps 2 for securing said arms in position on a plate which is to be ground. In the embodiment shown, the clamps 2 comprise vertically spaced, opposed upper and lower jaws 3 and 4, respectively, which are integral with the arms 1. The jaws 3 and 4 receive the plate therebetween. The upper jaws 3 are threaded to accommodate thumb screws 5 which clamp the arms 1 on the work in cooperation with the lower jaws 4.

At their other ends, the arms 1 terminate in vertical eyes 6. Secured by nuts 7 in the eyes 6 and depending from said eyes are hangers 8 in the form of vertical shafts. Set screws 9 releasably secure the hangers 8 against rotation in the eyes 6. Substantially rectangular metallic sleeves 10 are fixed on the lower ends of the hangers 8. Mounted in the sleeves 10 is a substantially channel-shaped guide 11 of suitable metal. The sleeves 10 are adjustable longitudinally on the guide 11. Set screws 12 secure the sleeves 10 in adjusted position on the guide 11. It will thus be seen that the guide 11 is mounted on the plate which is to be ground.

Referring now to Figures 1, 2 and 3 of the drawings, it will be seen that reference character 13 designates generally what may be considered a carriage which is operable on the work. The carriage 13 comprises metallic side plates 14 which include forwardly projecting, comparatively short and long upper and lower arms 15 and 16, respectively, said upper and lower arms being spaced from each other for the reception of the marginal portion of the work therebetween. The side plates 14 are secured at their rear end portions, as at 17, on the side members of a substantially U-shaped frame 18. The usual guard 19 of a conventional grinding tool 20 is secured at 21 for pivotal adjustment between the plates 14.

Fixed between the forward end portions of the arms 15 is a pair of spaced, parallel, transverse bars 22. Rollers 23 are journaled between the bars 22 for engagement with the upper surface 45 of the work.

Mounted beneath the forward end portions of the arms 16 is a metallic bar 24. A substantially U-shaped bar 25 is pivotally secured at 26 between the arms 16 for vertical swinging movement. Extending between the legs of the substantially U-shaped bar 25 is a bar 27. Rollers 28 are journaled between the bars 25 and 27. The rollers 28 are engageable beneath the work. Adjusting screws 29 are threadedly mounted in the bar 24 and engaged beneath the member 25

for raising and lowering the rollers 28 to accommodate plates of different thicknesses.

An arcuate, longitudinally adjustable brace or strut 30 is provided for vertically adjusting the tool 20 in the carriage 13 for grinding at different angles. The adjustable brace 30 comprises slidably adjustable sections 31 and 32 which are secured together by a screw 34. The element 32 is fixed to the front bar 22. The element 31 is secured at 33 on top of the grinder guard 19. The screw 34 is threadedly mounted in the element 31. A slot in the element 32 accommodates the screw 34.

Fixed beneath the U frame 18 and extending downwardly and rearwardly therefrom is an angular shank 35. A yoke 36 is adjustably mounted on the rearwardly projecting portion of the shank 35. The yoke 36 comprises, at an intermediate point, an eye 37 which accommodates the shank 35. A set screw 38 in the eye 37 secures the yoke 36 in adjusted position. As illustrated to advantage in Figure 10 of the drawings, the legs of the yoke 36 terminate in reduced spindles 39 having journaled thereon wheels or rollers 40. The wheels 40 are operable in the guide 11.

It is thought that the manner in which the invention functions will be readily apparent from a consideration of the foregoing. Briefly, to grind a straight edge, the guide 11 is mounted on the work through the medium of the hangers 8, the arms 1, et cetera. The carriage 13 is then mounted on the plate which is received between the upper and lower arms 15 and 16. With the wheels 40 on the yoke 36 traveling in the guide 11, the carriage 13 is manually fed on the plate with the head 41 of the tool 20 engaged with the edge to be ground. The U frame 18 may be adjusted forwardly or rearwardly relative to the yoke 36 at 37 for positioning the grinding tool properly relative to the work. If a beveled edge is to be ground, the screw 34 is loosened to permit the tool 20 to be swung upwardly or downwardly to the desired position on the carriage 13. As hereinbefore stated, the adjusting screws 29 permit the rollers 28 to be raised or lowered for mounting the carriage 13 properly on plates of different thicknesses. The wheels 40 are movable vertically in the guide 11 to permit operation of the carriage 13 on warped or otherwise irregular plates. By loosening the screw 34 and swinging 50

the tool 20 vertically on pivot bolts 21, a rounded edge may be ground. When a circular plate is to be ground, the carriage 13 is mounted for operation thereon and the guide 11, the arms 1, et cetera, are dispensed with. A straight edge may also be ground in this manner, if desired.

It is believed that the many advantages of a grinding tool guide constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

What is claimed is:

1. Means for grinding the edge of plate steel comprising, a carriage operable on a plate to be ground, said carriage including a pair of side plates, a grinding tool pivotally mounted for swinging adjustment between said plates, the plates including spaced arms for the reception of the work therebetween, and rollers journaled on the arms and operable on the work.
2. Means for grinding the edge of plate steel comprising, a carriage operable on a piece of work, said carriage including a U frame, side plates mounted on said U frame, a grinding tool pivotally mounted between said side plates, the side plates including spaced arms for the reception of the work therebetween, pairs of bars extending between the arms, rollers journaled between said bars and operable on the work, means for adjusting certain of the rollers toward or away from the work, and means for adjusting the grinding tool about pivotal mounting.
3. Means for grinding the edge of plate steel comprising, a pair of arms, means for detachably securing said arms on a piece of work, hangers depending from the arms, a substantially channel-shaped guide mounted on said hangers, a carriage operable on the work, said carriage including a U frame, side plates mounted on the U frame, rollers on the side plates operable on the opposite faces of the work, means for securing a grinding tool on the carriage for engagement with the work, a yoke mounted on the carriage, and wheels journaled on the yoke and operable in the guide.

THOMAS L. TAYLOR.
